UNITED STATES PATENT OFFICE.

JOHN KARMAZIN, OF DETROIT, MICHIGAN.

POSITIVE STOCK-FEED STOP.

Application filed May 12, 1926. Serial No. 108,463.

This invention relates to a machine for forming radiator elements of the type described in my copending application, Ser. No. 723,860, and particularly to a means for more positively stopping the strip of radiator forming material for its successive operations on its passage through the machine. In my prior application, Ser. No. 723,860, I have described a machine for forming radiator elements in which a strip of radiator element forming material is passed between a pair of cooperating punching dies and a plurality of tubular projections formed from and integral with the strip. The bottoms of these projections are perforated and the strip is cut off at predetermined lengths to form radiator elements which, when compacted together with the tubular projections in telescoping relation, form a radiator having water conduits passing therethrough. The strip of material is drawn through the machine by a pair of friction rollers which are continuously operated and which slide over the surface of the strip when the strip is held in position for the operation of the dies. The sides of the strip, after the punching operation, are trimmed by cutter guides which cut a rectangular piece of metal from the sides at each revolution of the machine. Shoulders are thus formed on the edge of the strip and when the strip is released by the dies and moved forward again by the rollers, these shoulders move forward until they contact with portions of the side walls of the dies, which stops the strip in position for another operation of the punches. The cutter guides, therefore trim the side edges of the strip and at the same time provide means to stop the strip intermittently as it passes through the machine. It has been found, however, in the use of very thin sheet metal for forming the radiator elements, after the strip has been trimmed by the cutter guides and moved forward so that the shoulders left by the cut out portions contact with the side walls of the die that the metal is not strong enough to stop the strip but has a tendency to curl or tear and allow the strip to move forward in the machine beyond the point for the next operation of the punches, so that the tubular projections do not line up with the punching dies for the next successive step. Also it has been found desirable, in some instances, to leave the radiator element entirely untrimmed on the sides, where- by a greater heat-radiating fin is provided and greater strength is provided in the fin by virtue of the roughened edges caused by the drawing of the metal to form the tubular projections. It is the principal object, therefore, of this invention to provide a means for positively stopping the progress of the strip of metal through the machine in the proper position for each successive operation of the dies without depending upon the cutter guides and the trimmed edges of the strip. Another object of the invention is to provide a positive stop mechanism for a radiator element forming machine which will engage one or more of the tubular projections on the radiator element forming strip, move forward with the strip a predetermined distance, stop the strip, after such forward movement, in position to be acted upon by the forming dies, and automatically return to its original position when the strip is held by the dies whereby it will be in position to engage the next succeeding tubular projections at the next operation of the machine. Another object of the invention is to provide a positive stop feed mechanism for radiator element forming machines which may be easily constructed at small cost. Another object of the invention is to provide a positive stop feed mechanism for radiator element forming machines which may be added to an existing machine without changing the design thereof. Other objects and advantages of the invention will appear as the description proceeds. In the drawings, in which one embodiment of the invention has been illustrated: Figure 1 is a sectional side elevation of a portion of the radiator element forming machine embodying my invention; Figure 2 is a sectional end view of the positive stopping means taken on the line 2-2 of Figure 1; and Figure 3 is a plan view of the portion of the radiator element forming machine embodying my invention. Referring more specifically to the drawings, the radiator element forming machine comprises a base 10, supporting a stationary die member 11 with which a reciprocating die member 12 carrying a series of punching dies 13 is adapted to cooperate. A pair of feed rollers 14 and 15 are rotatably mounted

105
110

on a bracket 14^b attached to the bed 10 of the machine and are continuously driven by suitable gearing 14^a communicating with the moving parts of the machine. A stationary 5 knife blade 17 and a cooperating movable knife blade 16 are mounted in front of the rollers 14 and 15 and are also connected by means of suitable levers and cams to the moving parts of the machine, so that the 10 movable blade 16 operates when a predetermined length of radiator element forming strip has been advanced between the blades 16 and 17. The lower roller 15 is preferably provided with grooves 15^a to accommodate 15 tubular projections on the radiator element forming strip 10^a as the strip is advanced between the rollers.

The above describes the radiator element forming machine substantially as constructed 20 prior to the present invention, which adds to this structure a bracket 18 which is attached to the bed of the machine and has a pair of arms 19 adapted to extend up on either side of the strip and pivotally support at 20 a 25 lever 21 which extends toward the reciprocating die member 12. An adjustable contact bolt 22 may be provided in a bracket 23, attached to the reciprocating die member 12 and may be adapted to engage the lever 21 at 30 every downward movement of the reciprocating die 12. A plate 24 integral with the lever 21 extends forwardly from the other side of the pivot 20, substantially parallel to the radiator element forming strip 10^a passing through the machine. The plate 24 is 35 cut out on the lower side thereof to form a guideway or track 24^a for a second plate 25 which is slidably retained against the plate 24 by means of strips 26 attached to the plate 24 by screws 27. A plurality of pins 28 are 40 rigidly attached to the slideable plate 25 and extend downwardly and are adapted to cooperate with the tubular projections 10^b on the strip 10^a of radiator element forming 45 material. A pin 29 is also rigidly attached to the plate 25 and extends upwardly through a slot 30 in the plate 24, which is long enough to permit the plate 25 to move longitudinally a distance equal to the 50 distance between the successive punching dies of the reciprocating die 12. A pin 31 is rigidly attached to the plate 24 and a spring 32 connecting the pin 31 and the pin 29 urges the plate 25 toward the pivot and normally 55 holds it in a position with the pin 29 against the rear of the slot 30. Springs 33 are attached between suitable hooks on the bracket 18 and pins 34 on the side of the plate 24 to normally hold the plate down in contact with 60 the strip 10^a of radiator element forming material.

In the operation of the machine, the reciprocating die member 12 moves downwardly forming the strip between the co-operating dies on the members 11 and 12 and

the contact bolt 22 depresses the lever 21 thereby raising the plate 24 and therefore lifting the pins 28 away from the radiator element forming strip. The spring 32 draws the plate 24 towards the pivot 20 and holds 70 it in its rearward position. When the die head 12 moves upwardly, the lever 21 is free to move upwardly and the plate 24 is pressed downwardly against the strip by the springs 33. The pins 28 engage certain of the 75 formed tubular projections 10^b on the radiator element forming strip 10^a before the dies 13, and the cutters 35 attached to the reciprocating die member 12 have been lifted out of the depressions on the radiator element forming strip. When these dies are clear of the strip, the rollers 14 and 15 pull the strip forward, the plate 25 moving forward with the strip until the pin 29 strikes the outer edge of the slot 30. The strip is 80 thereby stopped and held in this position until the dies 13 start to move down again with the head 12. The dies 13 engage the next successive tubular projections before the lever 21 is depressed. When the 85 lever 21 is depressed, raising the pins 24 from the strip, the dies 13 hold the strip firmly in place to complete the next forming operation and the plate 25 is again returned to its normal position, a section at the side 90 of the strip equal in length to the distance from one projection to the other being cut off by the cutters 35 so that the strip is again free to move forward one step when the die 12 is raised.

The stop mechanism is preferably mounted far enough away from the dies 13 to allow for the up and down movement of the strip 10^a as the tubular projections move into and out of the lower dies of the plate 11. Where 105 an untrimmed strip is desired, the cutters 35 may be omitted.

From the above it will be evident that I have provided a positive stop for the strip of radiator element forming material passing through the machine in which the tubular projections themselves are engaged, thus causing no damage to the strip and eliminating the necessity for the shoulders 35^a and the cutter guides 35 which may be used solely to trim the side strip, as illustrated in Figure 3. Any number of pins 28 may be used on the stop mechanism to engage the strip so that the strain of any one of the tubular projections caused by stopping the strip against the pull of the rollers 14 and 15 will be negligible.

Various modifications of the stopping means shown and described may be resorted to without departing from the spirit of the 125 invention or the scope of the appended claims.

What I claim as my invention is:

1. In a radiator element forming a machine, upper and lower cooperating die 130

- members, means to constantly urge a strip of radiator element forming material through said machine between said dies, and means adapted to positively grasp said strip 5 at each operation of the dies and permit said strip to move forward a predetermined distance whereby said strip is positioned between the dies for the next successive operation of the dies.
- 10 2. In a radiator element forming machine, a pair of cooperating die members, means to constantly urge a strip of radiator element forming material through said machine between said die members, and means operated 15 by one of said die members adapted to positively engage said strip when said dies are separated and permit said strip to move forward a predetermined distance, whereby said strip is positioned for the next operation 20 of the dies.
3. In a radiator element forming machine, a pair of cooperating die members, means acting to constantly urge a strip of radiator element forming material through said machine and between said die members, means to positively engage said strip and permit a limited forward movement thereof, means to normally hold said engaging means in contact with said strip and means to lift 25 said engaging means free from said strip when said die members are contacting with said strip.
4. In a radiator element forming machine, a stationary die member adapted to operate 30 on a strip of radiator element forming material, a reciprocating die member, means to constantly urge a strip of radiator element forming material through said machine and between said dies, means to positively engage said strip and permit a limited 35 forward movement thereof, means to normally hold said engaging means in contact with said strip and means cooperating with said reciprocating die to release said engaging 40 means when said dies are in engagement with said strip.
5. In a radiator element forming machine, a pair of cooperating dies, means to constantly urge a strip of radiator element forming material through said machine and 45 between said dies whereby tubular projections are formed on said strip, means to engage a plurality of said tubular projections, means to permit a limited forward movement of said engaging means, and means cooperating with said dies to lift said engaging means out of engagement 50 with said tubular projections when said die members are acting upon said strip.
6. In a radiator element forming machine, a pair of cooperating die members for forming a plurality of tubular projections on a strip of radiator element forming material by a series of successive punching operations, means to constantly urge said strip 55
- through said machine and between said die members, a plate normally parallel to said strip and pivoted at one end thereof above said strip, means slidably mounted on said plate to engage a plurality of said tubular projections and permit a limited forward movement of said strip and means cooperating with said die members to turn said plate about its pivot and lift said engaging means clear of said tubular projections when said 60 dies are acting upon said strip.
7. In a radiator element forming machine, a pair of cooperating die members for forming a plurality of tubular projections on a strip of radiator element forming material by a series of successive punching operations, means to constantly urge said strip through said machine between said dies, a plate pivotally mounted above and parallel to said strip, means slidably mounted on said 65 plate and adapted to normally engage a plurality of said tubular projections and permit a limited forward movement of said strip, means cooperating with said die members to rotate said plate about its pivot and lift said projection engaging means clear of said strip when said die members are acting on said strip and means to return said projection engaging means to its normal position when disengaged from said strip.
8. In a radiator element forming machine, a pair of cooperating die members for forming by successive punching operations a plurality of tubular projections on a strip of radiator element forming material, means to constantly urge said strip through said machine and between said die members, a plate pivotally mounted above and parallel to said strip, a second plate slidably mounted for limited longitudinal movement on the lower side of said first plate, means to normally hold said second plate in its extreme rearward position, a plurality of pins projecting downwardly from said second plate and adapted to engage a like number of the tubular projections on said strip whereby said strip may be moved forward a distance limited by the movement of said second plate, and means cooperating with said die members to rotate said first plate about its pivot whereby said pins are lifted clear of said strip when said die members are acting upon said strip and to permit said first plate to rotate in the reverse direction whereby said pins engage a new set of projections when said die members start to release said strip.
9. In a positive stop feed mechanism for a radiator element forming machine, a plate pivotally mounted above and parallel to the strip of radiator element forming material, a second plate slidably mounted for limited longitudinal movement on the under side of said first plate, spring means to normally hold said second plate in its extreme rear-

ward position, a plurality of pins extending downwardly from said second plate and adapted to engage with the tubular projections on said strip and means to rotate said first plate about its pivot and lift said pins out of engagement with said strip when said strip is held by said die members and to return said first plate to its normal position whereby said pins engage said strip when said die members are separated.

10. In a positive stop feed mechanism for a machine for forming radiator elements, means for engaging a strip of radiator element forming material, means to stop the forward movement of said engaging means when said strip has moved forward a predetermined distance whereby said strip is positively stopped in its course through the machine, means to release said engaging means from said strip when said strip is

held against forward motion by the forming dies of the machine, means to move said engaging means rearwardly and means to attach said engaging means to said strip before said strip is released by said forming dies.

11. In a radiator element forming machine, a pair of cooperating die members for forming by a series of successive punching operations a plurality of tubular projections on a strip of radiator element forming material, means to draw said strip through said machine, means to sever said strip in elements of a predetermined length, and means to grasp said strip and stop said strip after a limited forward movement thereof.

In testimony whereof I have affixed my signature to this specification.

JOHN KARMAZIN.
